UR D 12,705 EX

No. 12,705

Jan. 24, 1882

UNITED STATES PATENT OFFICE.

WALTER M. CONGER, OF NEWARK, NEW JERSEY.

DESIGN FOR A TEA-TRAY.

SPECIFICATION forming part of Design No. 12,705, dated January 24, 1882.

Application filed June 18, 1881. Term of Patent 14 years.

To all whom it may concern:

Be it known that I, WALTER M. CONGER, a citizen of the United States, residing in the city of Newark, county of Essex, and State of New Jersey, have invented a new and useful Improvement in Designs for Tea-Trays and Waiters, fully described and represented in the following specification and the accompanying photograph, forming a part of the same.

10 My design is shown in the annexed fac-simile as applied to an oval tray, but is equally applicable to round or square trays, and is intended to be produced in any desired colors.

To produce an effective photograph, the design is shown merely in black and white in the fac-simile, and the upturned edge of the tray being viewed obliquely, the proportions of the pattern are slightly distorted.

The essential feature of the design is a continuous series of scallops or arches disposed upon the flange with their convexity outward; and they may be produced in practice by lines, or merely by the contrasting of colors.

In the fac-simile a band of white is shown upon the bottom of the tray just adjacent to the flange, and the margin of the tray, outside the scallops, is also shown as white, with a bordering black line at the extreme edge. Over the center of each scallop is shown a flower of five or six petals, and a similar flower is supported in the outer notch, between the scallops, by a stem running down to the foot of the arch. From one side of each scallop a stem extends toward the center of the arch, and carries a pair of leaves and flower similar to the others.

The upper part of each arch is shown of a lighter shade than the lower, to indicate that the interior of the scallop may be filled with two colors. Thus the body of the arch may show the ground color of the tray, as black, 40 and the scallop be defined by a crescent of color, as blue, surmounting the black arch.

The flowers shown are preferably made of different colors in practice—as pink, white, and buff—and the external space between the 45 scallops of some color contrasting with the scallop itself, or with a different shade of the same color.

The band of color upon the bottom of the tray may be made of several stripes of color 50 or tints of the same color, or may be dispensed with. The ornamentation of the scallops in the manner described may also be varied at pleasure.

I therefore claim as follows:

1. The design for the flange of a tea-tray, consisting of the continuous series of scallops arranged with their convexity outward, substantially as shown and described.

2. In combination with the scallops disposed upon the flange of a tea-tray, as shown and described, the flowers arranged between and inside the scallops, as herein fully set forth.

In testimony whereof I have hereunto set my hand in the presence of two subscribing witnesses.

WALTER M. CONGER.

Witnesses:

THOS. S. CRANE,
WM. DIETZ.
